UNITED STATES PATENT OFFICE.

HERBERT W. LORENZ, OF HOUSTON, TEXAS.

ICE HOLDER.

Application filed March 5, 1925. Serial No. 13,335.

This invention relates to new and useful improvements in an ice holder.

One object of the invention is to provide an ice holder, of the character described, specially adapted to be secured on a vehicle running board, and designed to hold a block of ice, or other similar objects, securely on said running board.

Another object of the invention is to provide an ice holder which may be easily and cheaply produced, and easily applied, and one which is very effective for the purpose intended.

With the above and other objects in view, this invention has particular relation to certain novel features of construction, arrangement of parts and use, an example of which is given in this specification, and illustrated in the accompanying drawings, wherein—

Figure 1 shows a fragmentary side view of an automobile, showing the holder applied to the running board thereof.

Figure 2 shows a plan view of the holder.

Figure 3 shows an edge view thereof, partly in section.

Figure 4 shows a plan view of the securing bolt head, and

Figure 5 shows a fragmentary side view of the securing bolt employed.

Referring now more particularly to the drawings, wherein like numerals of reference designate similar parts in each of the figures, the numeral 1 designates the vehicle, as a whole, and the numeral 2 designates the running board on which there is a holder plate 3, preferably of metal and rectangular in form. This plate has the end openings 4, 4, aligned with similar openings, as 5 through the running board. These openings are provided to receive the securing bolts 6, 6. The lower ends of these bolts are threaded to re-

ceive the wing-nuts 7, 7, which are screwed thereon against the under side of the running board. The upper ends of these bolts have the heads 8, 8, which rest against the plate 3. 45 These heads have the upwardly projecting sharp teeth 9, 9, of any desired form.

In use the block of ice is placed on the plate 3 and the teeth 9 bite into the block and hold the same securely in place, while the 50 plate 3 serves to protect the running board.

What I claim is:—

1. A holder including a plate adapted to lie on a vehicle running board and provided with an opening, a bolt passing through said opening and adapted to pass, also, through said running board, an enlarged head formed with a sharp projecting tooth, on one end of the bolt and clamp nut on the other end of the bolt and disposed to clamp the plate 60 on the running board.

2. A holder including a plate adapted to lie on a vehicle running board and provided with a plurality of openings, bolts passing through said openings and adapted to pass, 65 also, through the running board, and enlarged head on the upper end of each bolt and adapted to abut said plate, and projecting tooth carried by each bolt and a nut on the other end of each bolt.

3. The combination with the running board of a motor vehicle of a bolt passing therethrough having one end enlarged forming a head which engages the upper side of the running board, threads carried by the 75 other end of the bolt, a nut for securing said bolt in said running board, and an upstanding projection carried by the head.

In testimony whereof I have signed my name.

HERBERT W. LORENZ.
